THOMAS ARMSTRONG, JAMES ARMSTRONG, AND WILLIAM ARMSTRONG,
OF PORT DEPOSIT, MARYLAND.

Design No. 2,813, dated October 22, 1867.

DESIGN FOR A COOK'S STOVE.

The Schedule referred to in these Letters Patent and making part of the same.

TO ALL WHOM IT MAY CONCERN:

Be it known that we, THOMAS ARMSTRONG, JAMES ARMSTRONG, and WILLIAM ARMSTRONG, all of the town of Port Deposit, in the county of Cecil, in the State of Maryland, have originated and designed a new Pattern for Cook-Stoves, called "Emerald," of which the following is a full, clear, and exact description, reference being had to the accompanying cuts or prints, making a part of this specification.

Our invention consists in the special form, proportion, and configuration of the patterns originated by us, and named "Emerald," for a cook-stove.

What we claim as our invention, and desire to secure by Letters Patent, is—

The design or pattern for the (Emerald) cook-stove, substantially as herein set forth and shown.

THOMAS ARMSTRONG,
JAMES ARMSTRONG,
WILLIAM ARMSTRONG.
